UNITED STATES PATENT OFFICE.

JOHN B. CORNWALL, OF MOLINE, ILLINOIS, ASSIGNOR TO THE BARNARD & LEAS MANUFACTURING COMPANY, OF SAME PLACE.

WOOD SPLIT PULLEY.

SPECIFICATION forming part of Letters Patent No. 429,564, dated June 3, 1890.

Application filed September 17, 1889. Serial No. 324,190. (No model.)

To all whom it may concern:

Be it known that I, JOHN B. CORNWALL, of Moline, in the county of Rock Island and State of Illinois, have invented certain new and useful Improvements in Wood Split Pulleys; and I do hereby declare that the following is a full, clear, and exact description thereof, reference being had to the accompanying drawings, and to the letters of reference 5 marked thereon, which form part of this specification, in which—

Figure 1 is a face view of my improved sectional or split pulley. Fig. 2 is a sectional view thereof, showing the parts detached. 15 Fig. 3 is a vertical sectional view of the same.

This invention is an improvement in sectional or split pulleys; and its objects are to provide a pulley that can be made of very small diameter without having any spokes or 20 hub, properly speaking, and which is sectional and can be fitted to various sizes of shafting, and which may be made of metal entirely, or, which I deem preferable, a combination of wood rim or periphery and central metal frame, all of which will be herein-after clearly explained and claimed.

Referring by letter to the drawings, A B designate, respectively, the two sections of a metal frame, which, as shown, is triangular 25 in cross-section, its corners, however, being cut off, so that really the frame might be called hexagonal. The part A comprises two sides of the triangular frame, being V-shaped, as shown, and part B comprises the complementary part or third side of the frame. In 30 the angle of part A is secured a block C, of wood, preferably transversely of the grain thereof. Said block is preferably secured in position by screws c passing through inwardly-projecting ears a of part A at the angle thereof, as shown. On the inner faces of 35 the sides of part A and about centrally thereof are cast offsets D D, which are bored and interiorly threaded for the engagement of bolts E E, that bind the part B to part A.

Part B has its sides b b bent upward, as shown, so that part B in cross-section contains one wide face and two narrow faces of the hexagon. 45

C' C' are blocks similar to blocks C and

projecting inwardly from the sides b b of part B, being secured thereto by screws passing through ears b' b' at the ends of said sides, as shown.

E E are bolts passing through openings in 55 part B, near the sides thereof, and through slots c' on blocks C', and engaging offsets D D of part A, as shown. The heads of these bolts being angular, they can be turned by a wrench, and thus part B securely bound to 60 part A, as shown. The blocks C C' C', it will be observed, all project inwardly and toward a common center and are at equal distances apart, and hence they can be readily clamped around a shaft W, as shown, and as part B of 65 the frame is adjustable toward or from part A to a certain degree it is obvious that the frame can be clamped accurately and firmly on a shaft, being properly centered by the blocks, and this adjustability of the frame 70 allows the pulley to be placed on shafts of slightly-varying diameters, and by shortening the length of blocks C C' or cutting away their inner faces the pulley can be readily fitted to any shaft that will pass through the 75 frame.

F F designate rim-sections secured to the sides of part A by means of screws F', as shown. Each section has its outer face dressed to form a third of the pulley-periphery, and F² designates a triangular block inserted between the meeting ends of sections F F and the corner of part A, as indicated, thus giving a solid appearance to the rim and bracing the ends of the sections. The sections preferably are of wood, but might be of 80 metal or other material.

f designates a rim-section similar to sections F, and fitted over and secured to part B, thereby completing the pulley and giving it an unbroken periphery. 85

f' f' are triangular blocks at the ends of section f, which fit between the outer faces of sides b of part B and the ends of sections f F, as shown, for the same purpose as block 95 F². The section f is secured to part B by means of screws G G, which pass through countersunk openings in section f, as indicated, and engage threaded openings in part B.

In adjusting the pulley upon a shaft the 100

blocks C' C' are first dressed or set to fit accurately upon the shaft, according to the diameter thereof. Then part A, with its rim-sections F F, is placed upon the shaft, and 5 part B placed opposite thereto and clamped to part A by the bolts E E, the blocks C C' centering the frame accurately upon the shaft. Section f is then secured to part B, and its 10 ends are dressed to fit accurately against the ends of sections F F, and the section f having a certain amount of adjustability on part B the periphery of the pulley can be maintained perfectly true, notwithstanding the part B has to be adjusted slightly toward or 15 from part A. The under side of section f is recessed to accommodate the heads of bolts E. The metal frame is centered and clamped upon the shaft with the sections F F before section f is placed in position; but as two- 20 thirds of the periphery of the pulley is comprised in sections F F the true centering of the pulley can be ascertained readily before placing section f in position. By simply removing section f the part B can be tightened 25 if the pulley becomes loose on the shaft.

The form of the metallic frame might be varied without omitting the essential features thereof, which are having it in two parts united by bolts independently of the rim-sections. 30

These pulleys can be made any face or rim width desired without regard to diameter. The grip-blocks, being contained in the iron frame, are not affected by any shrinkage of 35 the wood-work or by dampness. The clamping-bolts are contained in and bear only on the iron box and grain end of the hard-wood clamping-blocks, and are not liable to become loosened by shrinkage of the wood.

40 Having thus described my invention, what I claim as new, and desire to secure by Letters Patent thereon, is—

1. In a split pulley, the combination of a 45 triangular sectional frame, adapted to be clamped upon the shaft, with rim-sections secured directly to said frame, substantially as and for the purpose specified.

2. In a pulley, the combination of a metallic triangular two-part frame, united by bolts 50 and adapted to be clamped upon a shaft, with the rim-sections secured to said metallic frame independently of the clamping-bolts thereof, substantially as described.

3. The combination, in a pulley, of a triangular metallic sectional frame and blocks secured therein, and the means for uniting the parts of said frame around a shaft, with the rim-sections upon said frame, substantially as specified. 55

4. A pulley made in two separable parts, having an inner metallic frame made in two parts, clamping-blocks in said frame, and means for clamping said blocks, whereby the pulley can be secured upon a shaft, substantially as described. 60

5. In a pulley having neither arms nor hub, a sectional iron frame having a detachable and

adjustable side piece, clamping-blocks secured within said frame, and the adjusting and clamping bolts, substantially as and for 70 the purpose described.

6. In a wood split pulley, an adjustable sectional triangular iron frame inclosed within the rim-sections, the clamping-bolts uniting the parts of said frame independently of the 75 rim-sections, and clamping-blocks in said frame for centering the pulley upon a shaft, substantially as described.

7. In a split pulley, the combination of a triangular metallic angular frame and bolts 80 uniting the parts thereof, with rim-sections on and supported by the parts of said frame, substantially as described.

8. In a pulley having neither arms nor hub proper, an iron frame having one detachable 85 and adjustable part and having bolts for attaching and adjusting said removable part to the remaining portion of the frame, in combination with three clamping-blocks secured in said frame, whereby said pulley can be 90 clamped to a central shaft, substantially as and for the purpose specified.

9. In a wood split pulley, a triangular metallic frame or box having one removable and detachable part, clamping-blocks having the 95 grain of the wood endwise to the shaft, and exterior wooden rim-sections secured upon the metal frame, substantially as described.

10. The combination, in a pulley, of a sectional triangular metallic frame composed of 100 two parts united by bolts, substantially as described, and capable of being clamped and adjusted upon the shaft independently of the rim-sections, with the rim-sections rigidly united to the non-adjustable portion of said 105 frame, and the rim-section removably and adjustably connected to the adjustable portion of said frame, substantially as described.

11. The herein-described pulley, consisting of a triangular metallic frame formed in two 110 parts adjustably connected by bolts, and the blocks secured at the corners of said frame and adapted to clamp the shaft when the parts of the frame are clamped together, with the fixed rim-sections on one part of said 115 frame and the rim-section removably secured to the other part of said frame, all substantially as specified.

12. The combination, in a pulley, of the 120 angular metallic frame composed of a part A, having interior offsets perforated and screw-threaded, and the part B, united to part A by bolts engaging said offsets, the rim-sections F F, secured to part A, and the rim-section f, secured to part B, and the angular blocks 125 between the ends of the adjoining rim-sections, all substantially as and for the purpose described.

13. In a pulley, the combination of the triangular frame composed of the parts A and 130 B, part A having internal perforated and screw-threaded offsets and a clamping-block C, and part B having angular sides and clamping-blocks C' C' thereon, and the blocks

D D, uniting said parts, with the rim-sections F F, rigidly secured to part A, and the rim-section f, removably secured to part B, and the angular pieces interposed between the 5 ends of adjoining rim-sections and the corners of the frame, all substantially as and for the purpose described.

In testimony that I claim the foregoing as my own I affix my signature in presence of two witnesses.

JOHN B. CORNWALL.
